US00D572748S

(12) **United States Design Patent**
Markovitz

(10) **Patent No.:** **US D572,748 S**
(45) **Date of Patent:** **** Jul. 8, 2008**

(54) **EYEGLASS FRAME DESIGN**

(76) Inventor: **Aaron Markovitz**, 123 N. Ormond St.,
Bldg. 6, Ormond Beach, FL (US) 32174

(**) Term: **14 Years**

(21) Appl. No.: **29/257,228**

(22) Filed: **Mar. 31, 2006**

(51) **LOC (8) Cl.** **16-06**

(52) **U.S. Cl.** **D16/326**

(58) **Field of Classification Search** **D16/101, D16/300-342; D29/109-110; D24/110.2; 351/41, 44, 51-52, 62, 158, 92, 103-123, 351/140, 153; 2/426-432, 447-449, 441, 2/434-437**

See application file for complete search history.
